TWO-HAND CONTROL FOR SERVOMOTORS

Wallace F. Gayring, Minoa, N. Y., assignor to The Prosperity Company, Inc., Syracuse, N. Y., a corporation of New York

Application May 11, 1944, Serial No. 535,038

7 Claims. (Cl. 121—38)

This invention relates to two hand controls for pressure fluid, as pneumatic, motors for operating machines, as for instance, machines having an opening and closing movement, as garment and laundry presses, and particularly two hand controls, and has for its object a control wherein the fluid, as air, in passing through one control valve, when the valve is operated by its manual, operates means for locking the other valve, if it is not operated, so that both manuals must be operated substantially in unison and hence both hands of the operator must be employed while the machine, as a press, is closing.

More specifically, the invention has for its object a control including a pair of self-returnable manually operable valves of the combined intake and exhaust type normally arranged with the intakes closed and the exhausts open, these valves controlling the flow of motive fluid to a servomotor, as the cylinder of a cylinder and piston motor, and means operated by the flow of motive fluid or air through either valve when that valve only is operated for locking the other valve from operation, or locking the other valve from operation by blocking the operation of its manual.

The invention consists in the novel features and in the combinations and constructions hereinafter set forth and claimed.

In describing this invention, reference is had to the accompanying drawing, which is a diagrammatic view showing this control.

In the control system here illustrated, the flow of motive fluid, as compressed air, to the servomotor is indirectly controlled by manual valves and directly controlled by a master valve, and the master valve controlled by the manual valves.

1 designates the cylinder, 2 the piston, the cylinder being suitably mounted on the frame of the machine served by the motor, and the piston rod 3 being connected through suitable motion transmitting means, a portion of which is shown at 4, to the movable parts of the machine, as the movable press head of a laundry and garment pressing machine.

5 designates the master valve for controlling the flow of motive fluid from a feed line to the cylinder 1. The master valve may be of any suitable form, size and construction, as for instance, that shown in Davis Patent No. 2,341,696, issued February 15, 1944. It may, however, be omitted, and the flow of air to the motor controlled by a pair of manually operable control valves.

6 and 7 designate respectively a pair of control valves of the combined intake and exhaust type. These valves may be of any suitable construction.

They are here shown as each including a casing having a sliding valve member therein formed with an intake head 8 and an exhaust head 9, coacting with suitable seats, with the intake head 8 closed and the exhaust head open. The valve member is self-returnable from operated to its normal position, as by a suitable spring 10. The intake ends of the valve casings are connected by conduits 11 and 12 in multiple with a master feed line 13 for motive fluid, as compressed air. The valve casings of the valves 6, 7 have exhaust passages 14 and 15 respectively controlled by the exhaust valve heads 9. In this embodiment of the invention, the valve casings 6 and 7 are connected in multiple by conduits 16 and 17 to the master valve 5 instead of to the cylinder of the motor, through a conduit 18 common to both of them, the conduits 16, 17 opening into the valve casings of valves 6, 7 between the intake and exhaust valve heads.

19 and 20 designate the manuals for the movable members of valves 6, 7 respectively, these being here shown as pivoted at 21 and 22 to suitable supports 23, 24 and each having a push button portion 25 or 26 exposed in an opening in the support 23 or 24. The operating movement of each manual 19 or 20 is against a returning spring 27 or 28. The manual 19 or 20 thrusts against the stem 29 or 30 of the movable member or the control valve 6 or 7. Thus, when the manuals are operated in unison, their intake valve heads 8 will be opened and the exhaust valve heads 9 closed, and air will pass from the main line through the valve 6, conduits 16 and 18 to the master valve, and also from the main line 13 through the valve 7 and conduits 17, 18 to the master valve, operating the last valve to permit air to flow from the feed line 31 to the cylinder 1 to actuate the piston therein.

40 The means operated by the air passing through either valve 6 to prevent operation of the other valve, when the latter is not operated, as here shown, comprises movable members 32, 33 for the valves 6, 7 respectively. Each of these members has a vane 34 or 35 arranged in the path of the air exhausting through the exhaust port 14 or 15, said movable members having portions movable into position to block the operation of each manual 19 or 20, when the other only is operated.

45 50 The movable members 32, 33 are here shown as levers pivoted at 36, 37 respectively to the supports 23, 24 and having shoulders or teeth 38, 39 respectively, normally out of the path of complementary shoulders 40, 41 on the manuals 19 and 20 respectively, when the lever 32 or 33 is operated

by the current of air passing through the exhaust 14 or 15. The levers 32, 33 are here shown as counterbalanced as by weights 42, 43 respectively, the weights being sufficient to return the vanes after they have been actuated from the position shown in full lines to that shown in dotted lines by a current of air passing through the exhaust passage 14 or 15. When both manuals 19, 20 are operated in unison, the exhaust heads 9 are quickly closed and the intake valve heads opened, this operation being so quick that any air passing from the main line into the valve casings 6 and 7 does not have time to pass in an appreciable amount through the exhaust passages 14, 15 at least with force sufficient to operate the vanes 34, 35. With the control valves 6, 7 so operated, the air passes from the valve 6 through the conduits 16, 18 to the master motor 5 and from the valve casing 7 through the conduits 17, 18 to the master valve and from the master valve to the cylinder 1 of the servomotor. When, however, but one manual is operated, as for instance, the manual 25 to open the intake of the control valve 6 and close the exhaust thereof, air passes from the main line 13 through the conduit 11, valve casing 6, conduit 16 through conduit 17, casing of the valve 7 and out through the exhaust 15 of the casing of the valve 7, as this valve has not been operated. The current of exhaust air through the exhaust port 15 strikes the vane 35 and actuates the lever 33 to move its teeth 39 into interlocking engagement with the teeth 41 of the manual 20, thus blocking operation of the manual. The same operation takes place to block the operation of the manual 19 by operating the lever 32, when the manual 20 is operated and the manual 19 not operated. Thus, a particularly simple and efficient means is provided without the use of mechanical interlocks to lock one manual or its valve from operation, when the other manual only is operated, and thereby compelling both manuals to be operated simultaneously to effect the energization of the power cylinder 1.

The pivots 36, 37 for the levers 32, 33 are of any suitable antifriction type, as cone bearings.

The manuals are naturally and quickly operated by the operator and are usually held operated until the press closes or is in a safe position. Of course, this object may be defeated if the operator purposely plays with the manuals by depressing them so slowly that the air passing through the valve casing 6, 7, passes out predominately through the exhaust passages 14, 15, actuates the vanes 34, 35 and locks both manuals 19, 20 before they were fully depressed. This operation, however, prevents either exhaust valve from closing fully and therefore no air will build up in the master valve 5 and the machine will not operate. Slow operation of both manuals 25, 26 causes both to be locked from full operation.

A release valve R is provided to release the air from the master valve 5 after the cylinder 1 has completed its operation. This release is accomplished through pipe 50 and out exhaust port 51 of release valve R.

What I claim is:

1. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other unoperated valve, a pair of manuals for operating the valves respectively,

and means operated by the current of exhausting fluid from either of the control valves when the other control valve only is operated, to prevent the unoperated valve from operation.

5. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively, manuals for operating the valves, and means operated by the current of exhausting fluid from either of the control valves when the other control valve only is operated to lock the manual for the unoperated valve from being operated.

10. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively, manuals for operating the valves, and means operated by the current of exhausting fluid from either of the control valves when the other control valve only is operated to lock the manual for the unoperated valve from being operated.

15. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively, manuals for operating the valves, and means operated by the current of exhausting fluid from either of the control valves when the other control valve only is operated to prevent the unoperated valve from operation, said means including a movable locking member, one for each valve, each having a vane located in the path of the exhaust from the companion control valve.

20. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

25. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

30. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

35. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

40. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

45. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

50. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

55. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

60. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

65. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

70. A two hand control including a pair of self-returnable control valves of the combined intake and exhaust type normally arranged with their intakes closed and their exhausts open and connected independently in a power fluid feed line, so that power fluid in passing through either valve when either only is operated passes out through the exhaust of the other valve, a pair of manuals for operating the valves respectively,

of the operating movement of its companion manual to block the operation thereof.

6. A control for servo motors including a master valve, a pair of self-returnable control valves of the combined intake and exhaust type normally arranged with their intakes closed and exhausts open, and connected independently of each other in a power fluid feed line, for controlling the flow of motive fluid to the master valve, which control valves must be operated in unison to effect the flow of fluid to the master valve, a pair of manuals for operating the valves, one for each valve, conduits connecting the valves in multiple to the master valve and arranged so that said conduits are normally open to exhaust through the control valves and hence one only open to exhaust when the other valve only is operated, and means operated by the current of exhausting fluid from either of the manually operated valves, when only one is operated, to lock the other unoperated valve from operation.

7. A control for servo motors including a mas-

ter valve, a pair of self-returnable control valves of the combined intake and exhaust type normally arranged with their intakes closed and exhausts open, and connected independently of each other in a power fluid feed line, for controlling the flow of motive fluid to the master valve, which control valves must be operated in unison to effect the flow of fluid to the master valve, a pair of manuals for operating the valves, one for each valve, conduits connecting the valves in multiple to the master valve and arranged so that said conduits are normally open to exhaust through the control valves and hence one only open to exhaust when the other valve only is operated, and means operated by the current of exhausting fluid from either of the manually operated valves, when only one is operated, to lock the other unoperated valve from operation.

WALLACE F. GAYRING.
